Johan Emil Rylander, Stockholm, Sweden, as-
signors to Louise Gunnilla Violet Bennet, Kune-
borg, Stocksund, Sweden

Application October 14, 1940, Serial No. 361,175
In Sweden October 13, 1939

3 Claims. (Cl. 103—149)

(Granted under the provisions of sec. 14, act of
March 2, 1927; 357 O. G. 5)

Our invention relates to liquid pumps of the type comprising a casing and a flexible wall therein adapted to perform uni-directional wave-like movements with the crests of the wave in contact with a wall of the casing. The invention has for its object to provide a pump of the type referred to adapted to be operated without interruption even if the liquid to be pumped contains solid particles of varying sizes, as is often the case in, for instance, bilge-pumps or dock pumps. The invention is an improvement over the subject matter embodied in the Bennet application Serial No. 280,193, filed June 20, 1939.

We attain this object by mechanism illustrated in the accompanying drawing, in which—

Fig. 1 is a cross-sectional view taken on the line I—I of Fig. 2 of a liquid pump constructed in accordance with the invention, and Fig. 2 is a plan view of the pump, the cover thereof being removed.

The pump comprises an oblong casing 10 of rectangular cross-section and a cover 11 being suitably secured to the casing. At the end walls of the casing, there are provided bearings 12 and 13 for a helically shaped rod 14 hereinafter termed the helix. On either side of the helix there is provided a flexible band 15 and 16, respectively, which constitute displaceable walls positioned within the casing. The ends of said bands are secured to the bearings 12 and 13. The bands extend throughout the height of the casing so as to engage the cover 11 and the bottom wall of the casing with a tight fit. The distance between the ends of each band is so much less than the actual lengths of the bands that they are in contact with the helix 14 throughout the whole length thereof. The casing is provided with connections 17, 18, 19, 20 which communicate with the interior of the casing and serve as inlets and outlets for the liquid.

The crests of the band abut normally with a tight fit against lateral walls 21 and 22 which together with the cover and the bottom wall of the casing enclose the working chambers of the pump. The walls 21 and 22 can be displaced laterally and outwardly against the resistance of helical springs 23 while maintaining their sliding fit with the cover and the bottom wall of the casing, the springs 23 being inserted between said movable walls and the stationary side walls of the casing. The movable walls 21 and 22 are normally kept in the position shown in the drawing by the action of the springs 23 forcing said walls against stationary abutments 24 the position of which is determined

such that the crests of the bands 15 and 16 can slide on the walls 21 and 22, respectively.

If rotation is imparted to the helix 14, the bands will be actuated so as to perform uni-directional wave-like movements with their crests in contact with the walls 21 and 22, each band acting as an endless piston having a continuous uni-directional movement. Consequently, the apparatus will work as a displacement pump propelling a constant quantity of liquid for each revolution of the helix. The working chambers 25 and 26 confined by the bands and the movable walls will thus be moved in a certain direction depending upon the direction of rotation of the helix, for instance from the inlets 17, 18 to the outlets 19 and 20, respectively, and the liquid enclosed in said chambers will be propelled in the said direction. Obviously, the pressure exerted by the springs 23 on the movable walls 21 and 22 should be somewhat higher than the pressure exerted by the liquid enclosed in the working chambers so as to maintain the walls 21 and 22, under normal operation, in the positions shown in the drawing.

If, for some reason or other, a solid particle, such as a pebble or a piece of wood or metal, is drawn by suction into one of the working chambers, an excessive pressure will be set up at the place where one of the crests during its uni-directional movement comes into contact with the particle. Due to the said excessive pressure the respective wall 21 or 22 will be moved laterally outwardly against the action of the springs 23. As a result thereof, the particle can be moved into the outlet by the action of the crest travelling from the inlet to the outlet without any detrimental effect on the movable parts of the pump and without interruption of the operation of the pump. When the above named excessive pressure ceases the movable wall will be returned, by the action of the springs 23, into its normal position shown in the drawing.

Instead of providing relatively high-compression spring members 23 between the movable and stationary walls, the spaces between the said walls may be brought into communication with the outlet, as indicated by the pipe 27 (Fig. 2). As a result thereof, the pressures prevailing on either side of the movable wall will substantially counterbalance each other irrespective of variations in the pump pressure, and the springs 23 can be replaced by low-compression springs.

While we have shown an embodiment of the invention comprising two flexible bands, and

two working chambers arranged in parallel and in which the lateral walls are movable out of contact with the crests of the flexible band, it will be understood that the invention is not limited to the specific details thereof described with reference to the drawing.

What we claim is:

1. A pump comprising a working chamber, a flexible wall in said chamber, means for imparting to said displaceable wall a uni-directional wave-like movement, a second wall arranged to abut a crest of said displaceable wall, said walls being spaced from each other so as to constitute the working chamber, and resilient means arranged normally to maintain said second wall in contact with said crest and to permit said second wall of being removed from said crest due to excessive pressure on said second wall.

2. A pump comprising a casing, a working chamber in said casing, a displaceable wall in said chamber, means for imparting to said flexible wall a uni-directional wave-like movement, a movable wall slideable in said casing and arranged to abut a crest of said displaceable wall, said walls being spaced from each other so as

to constitute the working chamber, resilient means arranged normally to maintain said movable wall in contact with said crest and to permit said movable wall of being removed from said crest due to excessive pressure on said movable wall, and abutting means for maintaining said movable wall in normal position.

3. A pump comprising a casing, a working chamber in said casing, a flexible wall in said chamber, means for imparting to said flexible wall a uni-directional wave-like movement, a movable wall slideable in said casing and arranged to abut a crest of said flexible wall, said walls being spaced from each other so as to constitute the working chamber, resilient means arranged normally to maintain said movable wall in contact with said crest and to permit said movable wall of being removed from said crest due to excessive pressure on said movable wall, a second chamber in said casing bounded by said movable wall, and means for conducting working fluid to said second chamber.
